ORNAMENTAL CHAIN FOR A BRACELET OR SIMILAR ARTICLE

Richard E. Kunzmann, Providence, R. I., assignor to Kunzmann Chain Company, Providence,
R. I., a corporation

Application May 19, 1949, Serial No. 2,746

Term of patent 7 years

(Cl. D45—16)

To all whom it may concern:

Be it known that I, Richard E. Kunzmann, a citizen of the United States of America, residing at Providence, county of Providence, and State of Rhode Island, have invented a new, original, and ornamental Design for an Ornamental Chain for a Bracelet or Similar Article, of which the following is a specification, reference being had to the accompanying drawing, forming a part thereof.

Fig. 1 is a front elevational view of an ornamental chain embodying my new design;

Fig. 2 is a top edge view thereof;

Fig. 3 is a rear elevational view of the ornamental chain; and

Fig. 4 is a side elevational view thereof.

The links shown in full lines are repeated throughout the length of the chain as indicated by the broken lines across the center of the chain as shown in Figs. 1, 2 and 3.

I claim:

The ornamental design for an ornamental chain for a bracelet or similar article, as shown and described.

RICHARD E. KUNZMANN.
